UNITED STATES PATENT OFFICE.

JOHN A. FERGUSON, OF DENVER, COLORADO.

WALL CONSTRUCTION.

1,250,294.

Specification of Letters Patent. Patented Dec. 18, 1917.

Application filed October 6, 1916. Serial No. 124,104.

To all whom it may concern:

Be it known that I, JOHN A. FERGUSON, a citizen of the United States, residing at the city and county of Denver and State of 5 Colorado, have invented certain new and useful Improvements in Wall Construction; and I do hereby declare the following to be a full, clear, and exact description of the invention, such as will enable others skilled in 10 the art to which it appertains to make and use the same.

This invention relates to improvements in wall construction wherein the wall, instead of being solidly formed, consists of a concrete building block section, the blocks of 15 which have lateral spacing webs associated with a contiguously laid brick veneering wall section bonded thereto, and the complete structure providing a sectionally built 20 low wall, of maximum strength and desired thickness, with unobstructed vertical passages or air ducts throughout the same.

The invention resides wholly in the combined wall construction itself, no claim being 25 made to any of its constituent elements as dissociated therefrom, and from the following description, the novelty of the improved structure, as a whole, and its objects and advantages being so clearly apparent, it 30 is thought that a further initial statement thereof would only be unnecessary, as the invention will be fully understood after reference to the accompanying drawings, in which—

35 Figure 1, is a detail perspective view of an illustrative type of concrete block adapted for use in my improved wall construction, and

40 Fig. 2, is a perspective view of a part of a wall involving the principles of my invention in its construction.

The concrete block, as illustrated in detail at Fig. 1, comprises a flat base 1 having a pair of lateral projecting spacing webs 2 and 45 3, located at positions interiorly distant from the ends of said base, the said base being otherwise devoid of projections. As shown, the web 3 is provided with a recess or pocket 4, at its upper end, of a formation congruent 50 with the width and thickness of the bricks of the veneering section. A satisfactory method of providing this recessed pocket, in molding the blocks, is to simply omit a part of the upper portion of the desired webs.

These concrete blocks are disposed in ver-

tical alinement as a tier or wall section and are laid, as shown in Fig. 2, by breaking joints as customary. In the actual construction of my improved wall, all of the blocks 60 are not provided with the recess element mentioned, as bonding is only necessary at proper intervals, and the ones which are so recessed may manifestly have the recess formed in either of the abutting ribs 2 or 3, 65 as desired, to properly provide for the reception of the bonding headers hereinafter referred to.

5 designates the "stretcher" bricks of the veneering masonry wall, which bricks are 70 laid with their sides resting flat against the end faces of the webs of the block section, and 6 are half bricks or blind bonds, but which appear on the exterior surface of the wall as effective headers.

7 indicates true header bonds or whole 75 bricks, comprising a component element of the masonry wall itself, and the disposition and functioning of which form an essential feature of my invention.

As shown at the left of Fig. 2, these header bond bricks 7 are laid flush with and between the adjacent bricks in the same course or row and project beyond the inner surface of the brick wall, with their projecting portions fitting the recesses 4, or their equivalents, and as they are interposed throughout the wall at proper intervals they serve, as single elements, the multiple functions of being an actual component part of 90 the brick wall itself, as well as a bonding means between the brick wall and the spaced concrete block wall, and, in association with the blind bonds 6, lend to the veneer wall of brick the effect of a thickened and fully 95 bonded structure, a desired end in the construction of esthetic appearing buildings. Of course, the header bricks 7 are held secure in bonded relation with the concrete block section by the mortar layer joint, forming, 100 as it were, a monolithic joinder between the veneering brick wall section and the recessed spacing webs of the concrete wall section, thus providing an effective bonding means, a component element of the wall sections 105 themselves, incapable of rusting away or otherwise becoming disintegrated.

The concrete blocks at the right and center of Fig. 2 are shown as not being recessed, as shown at 4 in the left end block, for that 110 bonding is not essential excepting at desired intervals, and while it is evident that blind

bonds may be interposed alternately with the stretchers of the same row, I have only illustrated one blind bond 6 at the end of the top row opposite one of the abutting lateral webs. So also I have shown other blind bonds 6 and true header bonds 7 at different positions in the wall simply by way of illustration, it being understood that in actual wall construction the rows of headers may be 10 inserted in every several courses of brick, as desired.

I claim as my invention:—

15 In a wall construction, a concrete section composed of a series of building blocks, comprising a flat base having a pair of lateral spacing webs of the same depth as said base and spaced at a distance from the ends thereof, and substantially similar intermediate building blocks, one of the webs of which

latter blocks is formed with a recess at its 20 upper end; in combination with a veneer section composed of a series of bricks having their sides resting flat against the end faces of said spacing webs; and a series of whole tie-bricks transversely laid in the veneer section, during building operations, with one of their ends lying wholly between and flush with the adjacent bricks of the same course and their other ends projecting in an opposite direction to said spacing webs 25 and seated in bonded relation with the aforesaid recesses, the said recesses being of a depth and width congruent with the cross-sectional dimensions of said bricks, and the several elements functioning in combined 30 relation, substantially as described.

In testimony whereof, I affix my signature.
JOHN A. FERGUSON.
